ELECTRIC TRAY

Edson O. Sessions, Chicago, Ill.

Application January 5, 1937, Serial No. 119,129

5 Claims. (Cl. 219—19)

My invention consists of a tray adapted for use in serving light lunches and similar purposes where it is desired to have heating facilities for different articles to be served. By my invention 5 I provide a tray with a heating element or elements and one or more electric outlet sockets connected by suitable wiring in the body portion of the tray, so that the said electrical devices may be supplied with current by an electric cord 10 and connecting plug constituting a part of the tray assembly. The tray is also provided with switching devices for selectively connecting desired ones of the electric devices in the circuit, and in this connection I find it desirable to arrange 15 the switching devices so that the maximum electric load will not exceed the capacity of the fuses ordinarily employed in house lighting circuits.

The tray may be constructed of metal and ornamented as desired, either by the use of sheet metal, or cast metal, or if preferred, material of any suitable kind may be employed. My invention also includes electrically heated devices to be used with the electric tray and adapted for connection therewith and assembly thereon without the use of connecting wiring of any kind between said devices and the tray.

My invention will be best understood by reference to the accompanying drawing illustrating a 30 preferred embodiment thereof in which

Fig. 1 illustrates my tray in plan view,

Fig. 2 is a vertical, sectional view through the tray, taken longitudinally thereof along the line 2—2 in Fig. 1,

Fig. 3 is a vertical, sectional view through the tray shown in Fig. 1, taken along the line 3—3,

Fig. 4 is a vertical, sectional view to an enlarged scale of a part of the construction shown in Fig. 3, taken along the line 4—4,

Fig. 5 is a vertical, central, sectional view through the lower part of an electrically heated container, adapted to be used with the tray shown in Fig. 1,

Fig. 6 shows in front elevation and diagrammatically, a form of electric toaster adapted for use with the tray shown in Fig. 1, a part of the construction being shown in central, vertical, sectional view to better illustrate the electrical connecting devices, and

Fig. 7 is a diagrammatic circuit drawing of the electric connections employed in the tray illustrated in Fig. 1.

Similar numerals refer to similar parts throughout the several views.

As shown in Fig. 1, my electric tray consists

of a body portion 10 made of any suitable material to impart the requisite strength and stability to the device, the material illustrated in the drawing being sheet metal, although it will be understood that the tray may be made of any other suitable material that is preferred in any case. The tray 10 is provided with an edge rim 11 extending somewhat above the horizontal supporting surface of the tray, and is also provided with feet 12 to support it above any surface on which 10 it may be placed. The tray 10 is provided with an electrical heating element 13 having two heating coils 14 and 15, the coil 14 preferably developing a relatively large or high amount of heat, while the coil 15 preferably develops a relatively 15 small or low amount of heat. The heating element 13 has disposed above it, a metal grill or grating 16 to support above the heating element, any desired article or utensil to be heated, the upper surface of the grill being preferably substantially in the supporting surface of the tray 10.

The tray 10, is also provided as shown in Fig. 1, with two electrical and cylindrical outlet sockets 17 and 18 supported above the surface of the tray 10 by annular flanges 19 and 20 surrounding 25 them. The front portion of the tray has mounted thereon two electric switches 21 and 22 by which the flow of electric current to the heating coils 14 and 15 and to the sockets 17 and 18, may be controlled as desired.

As shown in Fig. 2 the bottom of the tray consists of a removable plate 23 of sheet metal or other suitable material which fits a recessed portion 10a of the tray structure, being held in place by screws 24 so that the wiring of the tray may 30 be effected, there being sufficient space between the bottom plate 23 and the top portion of the tray to permit this to be done. The upper portion of the tray at the location of the heating element 13, is provided with a downwardly extending annular portion 10b provided with vertically displaced shoulders, the lower one of which supports the heating element 13, and the upper one of which supports the grill 16 so that its upper surface is substantially in the plane of the 35 supporting surface of the tray. To guard against an undue amount of heat being communicated from the heating element 13 to the bottom plate 23 of the tray, I prefer to mount under the heating element and above the said bottom wall, a 40 screen or shield 25 of metal or other suitable material, so that there is a first air space between the shield and the heating element 13, and a second air space between the shield and the bottom wall 23, through which spaces air may freely circ-

30

55

culate. Where the heat developed by the heating element 13 is considerable, I find it desirable to provide perforations 23a through the bottom plate 23, under the shield 25 to admit cooling air 5 to the interior of the tray.

In Fig. 3, the relation of the flanges 19 and 20 to the upper portion of the tray 10 is more clearly shown, as well as the relation of the outlet sockets 17 and 18 to said flanges. As shown 10 in this figure, the top wall of the tray has secured thereto downwardly extending annular flanges 26 and 27 in line with the flanges 19 and 20, to receive the lower end portions of the outlet sockets 17 and 18 with a free fit, the flanges 26 and 27 15 being in-turned at their lower edges to support the outlet sockets 17 and 18 against vertical thrusts downwardly that may be exerted upon them in electrically connecting with them, desired electrical devices. The sockets 17 and 18 have 20 extending into them, through corresponding annular slots in the flanges 26 and 27, pins 28 and 29, which pins prevent movement upwardly of the sockets relatively to said flanges, and at the same time permit a limited amount of angular motion 25 of each socket relative to its supporting flanges, which feature of construction is more clearly illustrated for the socket 17 in Fig. 4, it being understood that the sockets 17 and 18 are similarly constructed and held in place in the 30 tray. As shown in Fig. 4, the pin 28 extends through an annular slot 28a through the flange 26, said slot having an angular extent of the amount which it is desired to permit the socket 17 to move in using the tray, the amount of angular 35 movement which I find convenient in practice, being from $\frac{1}{4}$ to $\frac{1}{3}$ of the circumference of the flange. The pin 28 is a free fit in the slot 28a, so that the socket 17 may be turned freely in its supporting flanges, to adapt the socket to the 40 particular angular position of the device used with the socket, that is found most convenient in one use or another of the tray.

As shown in Fig. 5, I illustrate at 30 the lower part of a utensil adapted to be heated by electric 45 connection with the tray, for example a coffee pot, the lower end of the part 30 being recessed and internally threaded, to receive corresponding external threads on a base portion 31, which base portion is recessed at its upper end to receive and 50 support a suitable electrical heating element 32. Below the heating element 32, the base 31 is provided with a second and smaller recess, containing a plate 33 of insulating material affording rigid 55 support for the electrical plugs 34 contained in a recess 35 below the plate 33 and in the lower part of the base 31, which recess 35 is open at its lower end and is of sufficient size to pass freely over the flanges 19 and 20 above described, so that the plugs 34 may enter the openings in either 60 of the sockets 17 and 18 and make electrical connection therewith with the bottom surface of the base 31 resting on the upper surface of the tray. The plugs 34 are connected by wires 36 with the heating element 32. By having the upper ends 65 of the sockets 17 and 18 in raised position above the upper surface of the tray 10 as above described, the plugs 34 may terminate above the bottom surface of the base 31 of the utensil illustrated in Fig. 5, so that the said plugs will not 70 interfere in any way with resting the utensil on any flat surface. Another advantage resulting from the raised position of the sockets 17 and 18, is that crumbs on the tray are prevented from entering said sockets and creating electrical disturbances. 75

In using the utensil shown in Fig. 5 with either of the sockets 17 and 18, the position of the apertures in the socket is noted and the utensil is turned until the plugs 34 are in alignment with the socket apertures, and the utensil is then 8 pressed downwardly, moving the plugs into electrical contact with the internal contacts of the selected socket, until the base 31 rests on the upper surface of the tray, after which if the angular position of the utensil is not convenient, 10 it may be turned to a position that is more convenient, depending upon the kind of utensil being used and whether the tray is being used from its side or its end.

In Fig. 6 I illustrate diagrammatically at 37, 15 an electric toaster adapted for use with the tray shown in Fig. 1, which toaster is provided with a heating element 38 connected with plugs 39 mounted in a recess 40 in the base portion of the toaster, in which recess said plugs are held in 20 vertical position by a block 41 of insulating material supported by and secured to the upper end of the wall of the recess 40 as indicated. The recess 40 provides that the plugs 39 may be entirely contained above the bottom plane of the 25 toaster 37, so as not to interfere in any way with supporting the toaster on a plane surface, the plugs 39 being adapted for connection with either of the sockets 17 and 18 in the manner described above for the utensil shown in Fig. 5, the toaster 30 being angularly adjustable as desired around the vertical axis of the connected socket, to suit the convenience of the user of the tray.

In Fig. 7, I illustrate diagrammatically the circuit connections which, with the embodiment 35 shown in Fig. 1, are made in the interior of the tray between the electric cord 42, the heating coils 14 and 15, the outlet sockets 17 and 18 and the switches 21 and 22, as follows:

Assuming that the plug 43 attached to the cord 40 42, is connected with suitable line wires, for example, of any ordinary house lighting system, line wire 44 is connected by wires 45 and 46 with one terminal of each of the plugs 17 and 18 respectively, and by a wire 47 with one terminal of each of the heating coils 14 and 15. The other terminal of the socket 17 is connected by a wire 48 with a contact 49 of the switch 21, and the other terminal of the socket 18 is connected by a wire 50 with a second contact 51 of said switch. The other terminal of the high heat coil 14 is 45 connected by a wire 52 with a third contact 53 of the switch 21, and the other terminal of the low heat coil 15 is connected by a wire 54 with a contact 55 of the switch 22, the blade portions of 50 the switches 21 and 22 being connected together and with the other line wire 56. By controlling the sockets 17 and 18 and the high heat coil 14 55 selectively by the switch 21, it will be observed that it is impossible to connect more than one of 60 said devices in circuit between the line wires 44 and 56 at the same time, so that if, for example, the electric devices intended for use with the outlet sockets 17 and 18 require not over 1,200 watts each to operate them, and the heating coil 65 14 requires not over 1,200 watts to operate it, as far as the switch 21 is concerned, it is impossible to connect a load of more than 1,200 watts with the line wires 44 and 56, thus insuring that the fuses used in house wiring for electrical utensils 70 in common use, will not be overloaded. The low heat coil 15 is intended to use a relatively small amount of power as a result of its relatively high resistance, for example, about 100 watts, and the switch 22 provides that the low heat coil 15 may 75

be used at the same time as the high heat coil 14 or as either of the outlet sockets 17 and 18, if desired, or it may be used alone when, for example, it is desired to keep any articles or utensils 5 warm. In this manner, the load on the line wires 44 and 56 may be controlled so as to not appreciably exceed the amount commonly required for a single electric toaster, a single electric flat iron, or other electrically heated device in common 10 use.

It will be understood that I do not limit myself to the arrangement of electrical devices illustrated with the tray, or to any particular utensils or appliances constructed to cooperate with the outlet 15 sockets of the tray, the construction shown in the drawing being illustrative of an embodiment of my invention which may be employed to meet general requirements. I do not, therefore, limit myself to the particular construction described, 20 as I may employ equivalents thereof without departing from the scope of the appended claims.

What I claim is:

1. In an electric tray, the combination of a body portion, an electrical heating element 25 mounted in said body portion, electrical utensil outlet sockets spaced from each other and from said heating element and mounted in said body portion, said body portion being hollow, an electrical connection cord extending from said tray, 30 selective switching mechanism carried by said tray, and electrical conductors in said body portion and connecting said sockets and said heating element with said cord and with said switching mechanism, whereby said sockets and said heating element may be selectively connected with said cord by said switching mechanism, said heating element including a low heat portion for connection with said cord independently of said 35 selective connection.
2. In an electric tray, the combination of a body portion, an electrical heating element mounted in said body portion, electrical utensil outlet sockets spaced from each other and from 40 said heating element and mounted in said body portion, said body portion being hollow, an electrical connection cord extending from said tray, selective switching mechanism carried by said tray, and electrical conductors in said body portion and connecting said sockets and said heating element with said cord and with said switching mechanism, whereby said sockets and said heating element may be selectively connected with 45 said cord by said switching mechanism, said sockets having limited angular movement relatively to said body portion, whereby a utensil con-

nected with either of said sockets may be turned a limited amount on the tray.

3. In an electric tray, the combination of a body portion, an electrical heating element supported by said body portion, electrical outlet 5 sockets supported by said body portion for connection with separate electrically heated utensils, two electrical supply conductors, an electrical switch having spaced active contacts, first electric wires selectively connecting said active contacts with one terminal of each of said sockets and of said heating element, and second electric wires connecting the other terminals of said sockets and of said heating element with a first one of supply conductors and also connecting the 10 other of said supply conductors with said switch, whereby said switch can select and operatively connect but one of said sockets and heating element at any time.

4. In an electric tray, the combination of a body portion, an electrical heating element supported by said body portion, electrical outlet 15 sockets supported by said body portion, two electrical supply conductors, a first electrical switch having spaced active contacts, first electric wires 20 selectively connecting said active contacts with one terminal of each of said sockets and of said heating element, second electric wires connecting the other terminals of said sockets and of said heating element with a first one of supply conductors and also connecting the other of said supply conductors with said switch, whereby said 25 switch can select and operatively connect but one of said sockets and heating element at any time, said heating element including a high heat 30 portion connected with said first switch and also a low heat portion, a second electrical switch, and third electric wires connecting said low heat portion and said second switch with said supply conductors, thereby controlling the operation of said 35 low heat portion by said second switch.

5. In an electric tray, the combination of a body portion, an electrical outlet socket carried by said body portion and opening upwardly, and an electrically heated utensil having vertically 45 disposed connection plugs in its lower portion for connection with said socket by downward movement of said utensil over said socket to rest upon said body portion, said socket having angular movement relatively to said body portion, whereby 50 with said utensil on said body portion with its plugs in said socket, said utensil may have angular movement around the axis of said socket.
